UNITED STATES PATENT OFFICE.

ALFRED L. BERNARDIN, OF EVANSVILLE, INDIANA.

BOTTLE-CAP.

1,287,191.

Specification of Letters Patent. Patented Dec. 10, 1918.

Application filed November 3, 1917. Serial No. 200,191.

To all whom it may concern:

Be it known that I, ALFRED L. BERNARDIN, a citizen of the United States, and a resident of Evansville, in the county of Vanderberg and State of Indiana, have invented a new and useful Improvement in Bottle-Caps, of which the following is a specification.

My present invention relates generally to bottle caps and more particularly to bottle 10 caps for catsup bottles and the like of the type described and claimed in my Patent No. 1,244,413, granted October 23, 1917.

The primary object of my present improvement is the provision of a cap construction which will avoid the necessity of screwing the cap upon the bottle and which will thus avoid a great waste of time in opening and closing a bottle during the gradual using of the contents thereof and 20 also avoid the initial manual screwing of the cap prior to the application of power thereto for compressing the sealing member in the first instance.

In the accompanying drawing illustrating 25 my present invention—

Figure 1 is a perspective view of a portion of a bottle neck provided with my improved cap sealed thereon,

Fig. 2 is a vertical sectional view illustrating the cap in inoperative connection 30 with the bottle neck before sealing,

Fig. 3 is a similar view with the parts in sealed position,

Fig. 4 is a side view of the bottle neck as 35 I propose to construct the same.

Fig. 5 is a horizontal sectional view taken substantially on the line 5—5 of Fig. 3,

Fig. 6 is a side view of one portion of a cap of slightly modified form, and

Fig. 7 is a vertical sectional view through 40 the modified cap upon a bottle neck.

In the construction proposed by my present invention the bottle cap has a locking means in connection with a bottle engageable by rectilinear movement of the cap with respect to the bottle to engage and clamp a portion of the latter, and as in my patent above referred to, is also provided with sealing means for engagement with 45 a separate portion of the bottle in the first instance, so that after the bottle has been filled by the manufacturer it is simply necessary to place the open end of the cap upon the mouth of the bottle and the pressure member for compressing the internal sealing 50 disk of the cap serves in the present in-

stance to force the cap onto the bottle neck to move that part of the locking means carried thereby beyond that part of the locking means carried by the bottle and shift 60 the sealing means into the operative position for engagement with an annular shoulder of the bottle provided for the reception thereof.

My present invention thus distinguishes 65 from my patent, above referred to by virtue of the elimination of the necessity of rotating the cap, which must, of course, be done by hand so as to engage the cap with the bottle in the first instance and makes it 70 possible to perform both of these operations by the compressing member when the bottle is initially filled and also enables more ready and quick engagement of the cap with the bottle and disengagement of the cap from 75 the bottle in the after use of the bottle during the gradual consumption of the contents thereof.

Referring specifically to the figures of the drawing before described my present invention provides a bottle neck 10 having adjacent its open end or mouth an annular rounded enlargement 11 and provided below the said enlargement with an annular shoulder 12, the latter providing a lower 80 square face and being farthest removed 85 from the mouth 13 of the bottle neck upon which in the initial sealing of the bottle the usual cork or sealing disk 14 of other material is disposed.

To coöperate with the bottle neck so formed the cap 15, which is closed at one end at 16 and is open at its opposite end, is provided at a point intermediate its ends with an annular series of depressed portions 90 or indentations 17, its diameter being so related to the diameter of the bottle neck that these indentations may be pressed downwardly over the enlargement 11 of the bottle neck by virtue of resiliency of the cap 100 and the indentations 17 so as to lock the cap upon the bottle neck. This construction provides for quick and convenient attachment and detachment of the cap by the consumer during the gradual consumption 105 of the contents of the bottle, and inasmuch as the indentations 17 of the cap in a single annular series move past the enlargement 11, the said construction provides also for the use of a sealing means by further compressing the cap 15 to force the same longitudinally of the bottle neck so as to thus 110

compress the sealing disk 14 against the mouth 13 of the bottle neck and between the same and the closed end 16 of the cap.

As above stated the sealing disk may be 5 constructed of various materials suitable in the formation of an air and liquid-tight joint and in compressing this disk a suitable pressure member 18 as seen in Fig. 3 is employed within a suitable machine for this purpose, 10 the action of which forces the cap inwardly upon the bottle neck to provide for its sealing independent of the action of the indentations 17 in connection with the bottle neck enlargement 11, which latter would be insufficient for the purpose of supporting the 15 parts in sealed position.

As in my patent above referred to the inner edge of the cap 15 around its open end has an extension metal band 19 so as to 20 permit of ready flanging or rolling of the inner free edge thereof beneath the lower edge of the bottle neck shoulder 12 as seen clearly in Fig. 3, the opposite edge of this extension band being connected to the said lower 25 inner edge of the cap around its open end by means of a seam 20, which latter may be of any suitable type as for instance an inter-folded or lap joint seam, although preferably of the bead seam type as clearly shown 30 in Figs. 2 and 3, in order that the cap may upon complete removal of this extension band remain as of the usual construction for application or reapplication to the bottle in the regular way.

The ends of the band 19 are joined in any suitable manner, as for instance, by an inter-folded seam as seen at 21 in Fig. 5 in particular, one extremity projecting in the form of a tongue 22 to provide for ready and 40 complete ripping or tearing of the band completely from the cap and from the bottleneck shoulder 12 in breaking the seal in the first instance, or the well known tongue and slot connection may be utilized. When formed 45 of soft material as described, however, the band may, if so desired, be readily cut away from the bottle neck shoulder and from the cap by a knife or other implement and the tongue 22 dispensed with.

It is obvious from the foregoing that in 50 the initial sealing process after the bottle is filled in the first instance, the cap 15 need only be placed upon the mouth of the bottleneck and may be forced to the position 55 shown in Fig. 2 with the indentations 17 in operative engagement with the bottle neck enlargement 11 either by hand or by the pressure element 18 which also forces the indentations past the enlargement as seen 60 in Fig. 3 in order to compress the sealing disk 14, the fact that the cap and the neck have locking means engageable by rectilinear movement of the cap onto the neck, permitting this operation to be accomplished 65 in either of the manners stated.

Proceeding in either way mentioned, it is apparent that when the pressure member 18 has compressed the sealing disk 14 and moved the parts to the position shown in Fig. 3, it is simply necessary to flange or 70 roll the inner free edge of the extension band 19 around the lower edge of the bottle neck shoulder 12, as seen at 19^a in Fig. 3, to fasten the entire cap in sealed position and in such manner that this seal may be readily 75 broken when it is desired to open the bottle and the band 19 disassociated from the cap in its entirety so that the latter may be taken off and reapplied by rectilinear movement with respect to the bottleneck during the 80 gradual consumption of the contents of the bottle in use.

As seen in Figs. 6 and 7 the indentations 17^a of the cap 11^a may be more nearly circular and the lower portion of the cap 4^a may 85 have an outwardly offset flange 11^b for engagement by an upper inner flange of the band 19 instead of the seam 20 before described.

It is obvious, therefore, that my present 90 improvements simplify the construction of both the bottle neck and cap in addition to the operations necessary for their association with and disassociation from one another as compared to the construction described and claimed in my patent above referred to.

I claim:—

1. The combination with a bottle neck having an annular rounded enlargement 100 and an annular shoulder below the enlargement, of a cap containing an inner sealing member for engagement with the bottle mouth and provided with an annular series of indentations engageable with the annular 105 enlargement of the bottle neck and movable past the same by rectilinear movement of the cap with respect to the bottle neck when pressure is applied to the cap for compressing the said sealing member and a sealing 110 band connected to and carried by the lower edge of the cap and projecting beyond the bottle neck shoulder when the sealing member is compressed and bendable into engagement with said shoulder to hold the cap in 115 sealed position.

2. The combination with a bottle neck having an annular rounded enlargement and an annular shoulder below the enlargement, of a cap containing an inner sealing 120 member for engagement with the bottle mouth and provided with an annular series of indentations engageable with the annular enlargement of the bottle neck and movable past the same by rectilinear movement of the 125 cap with respect to the bottle neck when pressure is applied to the cap for compressing the said sealing member and a sealing band connected to and carried by the lower edge of the cap and projecting beyond the 130

bottle neck shoulder when the sealing member is compressed and bendable into engagement with said shoulder to hold the cap in sealed position, said sealing band having a detachable connection with the cap and removable from the latter to permit of subsequent coöperation of the cap and bottle neck through the indentations and enlargement thereof respectively.

3. The combination with a bottle neck, of a cap having an internal sealing member engageable with the mouth of the bottle when pressure is applied to the cap to compress the said sealing member, said cap and said

bottle neck being provided with relatively 15 engaging means when the cap is so compressed to hold the cap in sealed position and said cap and bottle neck having relatively engaging means adapted to hold the cap locked upon the bottle neck independent of 20 the sealing means and shiftable into and past their engaged position in the same direction as required to bring the sealing means into operative relation.
